CLAIM

The ornamental design for an electronic display, as shown and described.

DESCRIPTION

FIG. 1 is a rear perspective view of an electronic display showing our new design;

FIG. 2 is a rear view thereof;

FIG. 3 is a first side view thereof, the opposing side view being the same; and,

FIG. 4 is a second side view thereof, the opposing side view being the same.

The dash-dash-dash broken lines in the Figures are for the purpose of illustrating unclaimed portions of the electronic display and form no part of the claimed design. The dash-dot-dash broken lines are boundaries of the claimed design. It is understood that the claimed design extends to these boundaries but does not include the boundaries. The shade lines in the Figures show Contour and not surface ornamentation. The front of the electronic display is not illustrated and forms no part of the claimed design.

1 Claim, 3 Drawing Sheets
